UNITED STATES PATENT OFFICE.

EDWARD A. CUNNIFE, OF WALTHAM, MASSACHUSETTS, ASSIGNOR TO DRAPER CORPORATION, OF HOPEDALE, MASSACHUSETTS, A CORPORATION OF MAINE.

SHUTTLE-FEELER THREAD PARTER AND CLAMP.

Application filed April 23, 1926. Serial No. 104,048.

This invention relates to shuttle feeler thread parters and clamps whereby the out-going filling is parted and clamped on replenishment of filling and held for the action 5 of the temple thread cutter.

It is now the ordinary practice to provide filling replenishing looms with means for severing the out-going filling and clamping the end leading to the cloth selvage, and in 10 some cases such parting and clamping means is carried by the shuttle feeler. Since the filling leading from the filling carrier or bobbin to be ejected on replenishment of filling, extends from the cloth selvage to the 15 shuttle eye at the time the shuttle feeler is moved to its rearward operative position, it frequently happens that the length of filling between the cloth selvage and the shuttle is so slack or kinky that the filling fails to be 20 engaged by the parting and clamping means, the effect being that portions of the old filling will be carried back into the shed and form imperfect cloth.

One of the objects of the present invention 25 is to provide a shuttle feeler thread parter and clamp with a thread positioner or lifter arranged in cooperative relation with the parter and clamp to properly position the thread for the action of the parting and 30 clamping means. In accordance with the present invention, the thread positioner or lifter is of plate form, having a lower edge portion which is curved from rear to front in a progressively increasing curvature, such 35 that when the shuttle feeler and the lay are relatively moved, the progressively increasing cam surface of the thread lifter will cause such thread lifter to first be projected beneath the filling and then gradually rise to 40 locate or position the out-going thread for the action of the shuttle feeler thread parter and clamp.

The present invention and all the features thereof will best be made clear from the following description and the accompanying drawings.

In the drawings:

Fig. 1 is a perspective view of sufficient portions of a loom to show the present invention associated therewith and with the shuttle feeler, the thread parter and clamp and thread lifter being in their open or thread receiving position;

Fig. 2 is a side elevation showing more 55 particularly the features of the thread parter

and clamp and thread lifter, with the parts in closed or thread parting and clamping position;

Fig. 3 is an enlarged perspective view showing the shuttle feeler and lay as being 60 relatively moved in a direction of approach and the thread lifter as being gradually moved to lift the thread into the sphere of the thread parter and clamp;

Fig. 4 is a view similar to that of Fig. 3 65 showing the thread lifter as having raised the thread into position for engagement by the thread parter and clamp; and

Fig. 5 is a view of a modification of the 70 present invention.

In accordance with the present invention, the shuttle feeler thread parter and clamp is of the general type now in use and is normally retained in a frontward position until call for replenishment of filling and is thereupon moved rearwardly into shuttle feeling position. Associated with such shuttle feeler 75 is a thread parter and clamp and a thread lifter, the latter of which positions the thread for the action of the parter and clamp 80 as the lay and shuttle feeler move in a direction of relative approach. To prevent overthrow of the thread as it is being lifted by the thread lifter, the present invention provides the thread lifter with a progressively 85 increasing cam surface which is engaged by the lay and causes the thread lifter to be moved without shock and lift the thread into position for the action of the thread parter and clamp. 90

The loom frame has secured thereto the usual bracket 1 to which is pivoted at 2 the lower hub portion 3 of the shuttle feeler 4, the upper rear end portion of which at 5 is provided with the usual upper and lower 95 jaws. The shuttle feeler 4, as indicated in the present instance, is provided with a pin 6 which is engaged between the yielding jaws 7 and 8, and such jaws 7 and 8 are actuated on call for replenishment of filling 100 to move the shuttle feeler into its rearward feeling position, as indicated in Fig. 1. The means for moving the jaws as described forms no essential part of the present invention and being well understood it is not 105 herein illustrated.

The shuttle feeler 4, as shown, is guided in its movements towards and from the front of the loom by a guide 9 which may extend from the bracket 1, and secured to 110

the bracket 1 is the upstanding arm 10 having a thread parter and clamp trip member 11 which may be of usual construction and serve to open the thread parter and clamp as the shuttle feeler moves to its rearward shuttle feeling position. Such parts, however, are not of the essence of the present invention, and being well understood, further illustration and description thereof is 10 unnecessary.

Secured to the shuttle feeler is the fixed parting member or cutter 12, the cutting edge of which is adapted to cooperate with the movable thread parting and clamping member 13 which is herein shown as pivotally connected to the shuttle feeler by a bolt or stud 14. The movable thread parting and clamping member 13 has a front tail portion 15, as usual, from which extends the pin 16 for cooperation with the opening trip 11 as the shuttle feeler moves to its rearward feeling position.

Secured to and extending laterally from the upper portion of the shuttle feeler is a fixed pin 17 which extends through an opening 18 formed in the front portion of the movable thread parting and clamping member 13, and the opening 18 is of sufficient dimensions to permit the movable parting 30 and clamping member to move in its cutting and clamping operations.

Pivottally mounted upon the pin 17 is the movable clamping member 19 which is provided with an elongated slot 20 through 35 which passes the pin 14 on which the movable parting and clamping member 13 is pivoted.

From the construction thus far described it will be apparent that the movable parting 40 and clamping member 13 will act upon the thread to cut it in cooperation with the fixed cutting or parting blade 12 at one side and that at its opposite side will cooperate with the movable clamping member 19 to clamp 45 the thread which leads towards the cloth selvage.

In order that the parting and clamping member 13 and the movable clamping member 19 may be held in cooperative relation, 50 a spring washer 21 rests upon the outer face portion of the movable clamping member 19 between the head 22 of the bolt 14 and the movable parting member.

The end 23 of the spring washer 21 is 55 turned inwardly and secured to the movable clamping member 19, with the result that as the movable clamping member 19 is moved on its pivotal support 17, it will cause the washer 21 to swing about its pivotal support 14 for a purpose that will presently appear.

Secured to the movable clamping member 19 is the thread positioner or lifter 24 which 60 comprises a plate preferably connected to the movable clamping member 19 by pins

25 and having its rearwardly extending portion 26 projecting rearwardly beyond the end of the shuttle feeler as a thin lifting member which is adapted to pass below the filling *a* and into the recess 27 formed in 70 the upper surface or raceway of the lay 28.

The thread positioner or lifter, as shown, is of the plate form, and its lower edge portion is provided with a cam surface 29 which extends from the end of the positioner or lifter frontwardly in a progressively increasing curve which finally terminates at the point 30 at the lower edge of the lifter. The construction is such that as the progressively increasing curve 29 is met by the front edge portion of the lay, the lifter will be progressively raised without subjecting the overlying thread *a* to any undue shock or disturbance calculated to 85 misplace it with respect to the parting and clamping members.

Extending upwardly from the movable clamping member 19 is an arm 31 which, as shown, is secured to the movable clamping member at its pivotal point, and the upper end portion 32 has connected to it a spring 33, the other end of the spring being secured to a pin 34 on the shuttle feeler tending normally to depress the movable clamping member 19 and its connected lifter 24. 90

As hereinbefore noted, the washer 21 is secured at 23 to the movable clamping member 19 and consequently is moved about its pivotal support 14 as the clamping member 19 is raised or lowered. The present invention takes advantage of this fact to provide a stop shoulder 35 on the washer to limit the downward or opening movement of the clamping member and connected lifter under the action of the spring 33. The washer 21 is provided with a second shoulder 36 which engages the top surface 37 of the lifter when the lifter and movable clamping member are raised as hereinbefore described, thereby limiting the movement of these parts in the opposite direction. 105

As indicated in Fig. 5, the positioning device or lifter may be mounted in a slot formed in the shuttle feeler and be pivoted directly to the shuttle feeler, but in this case, as in the preferred form of the invention above described, the lower edge portion of the thread positioner or lifter is provided with the progressively increasing curved or cam surface to lift the thread without shock into its position for engagement by the thread parter and clamp. 115

The shuttle feeler, as indicated in Fig. 5, is provided with a slot 38 in which is pivotally supported at 39 the thread lifter 40, the lower edge surface 41 of which progressively increases in curvature towards the front of the loom. The thread lifter 40 has the upwardly extending arm 42 housed with- 120 125

in the feeler, and connected to the upper end of the arm 42 is a spring 43, the other end of which is secured to a pin 44 which normally acts to depress the rear end portion 5 of the thread lifter 40.

From the construction described, more particularly with reference to Fig. 1, it will be apparent that when the shuttle feeler is moved backward to its shuttle feeling position, the tapering end portion 26 of the thread lifter will pass beneath the thread *a* and as the lay moves forwardly, the progressively increasing curved edge portion 29, 30 of the thread lifter will be engaged by 10 the lay and cause the thread lifter, and with it the movable clamping member, to be turned about their pivotal support 17 against the tension of the spring 33 to thereby position the thread, first, as indicated in Fig. 3, and then as the lay finally reaches its full forward throw, the lifter and movable clamping member will have the thread positioned as indicated in Fig. 4, ready for the action of the thread parter and 20 clamp, and as the thread parting and clamping member 13 is actuated during forward movement of the lay, the movable thread clamping member 19 will lift the thread already positioned by the thread positioner, so that as the movable parting and 30 clamping member 13 closes, it will first act to clamp the thread and then cut it, so that as the shuttle feeler moves to its front position, the end leading to the cloth selvage 35 will be held by the clamping members to present the thread to the temple thread cutter.

What is claimed is:

1. In a loom, the combination of a shuttle 40 feeler having a thread parting and clamping member, a thread lifter for positioning the thread for engagement by the parting and clamping member and actuated by relative movement of the lay and shuttle feeler, 45 and a second clamping member moved by the thread lifter to present the thread for the clamping action of the two clamping members.

2. In a loom, the combination of a shuttle feeler having a fixed thread parter and a 50 movable combined thread parting and clamping member, a thread lifter for positioning the thread for engagement by said member and actuated by relative movement of the lay and shuttle feeler, and a second 55 clamping member which is moved by the thread lifter as it is actuated to place the thread for engagement of the two clamping members before it is parted.

3. In a loom, the combination of a shuttle 60 feeler having thread parting and clamping members, a thread lifter extending from one of the clamping members and adapted to be actuated by relative movement of the lay and shuttle feeler to lift the thread and 65 cause the clamping member from which it extends to be moved to place the thread for engagement between the clamping members.

4. In a loom, the combination of a shuttle 70 feeler having thread parting and clamping members, a thread lifter extending from one of the clamping members and adapted to be actuated by relative movement of the lay and shuttle feeler to lift the thread and 75 cause the clamping member from which it extends to be moved to place the thread for engagement between the clamping members, and a spring normally acting to hold the lifter and connected clamping member in 80 thread disengaged position.

5. In a loom, the combination of a shuttle 85 feeler having thread parting and clamping members, a thread lifter extending from one of the clamping members, and adapted to be actuated by relative movement of the lay and shuttle feeler to lift the thread and cause the clamping member from which it extends to be moved to place the thread for engagement between the clamping members, and stops for limiting the movements of the 90 thread lifter and connected clamping member.

In testimony whereof, I have signed my name to this specification.

EDWARD A. CUNNIF. F.
